US00D988132S

(12) **United States Design Patent** (10) **Patent No.:** **US D988,132 S**
Twiss et al. (45) **Date of Patent:** **** Jun. 6, 2023**

(54) **METAL CONTAINER CLOSURE**

(71) Applicant: **Crown Packaging Technology, Inc.**,
Alsip, IL (US)

(72) Inventors: **Matthew Twiss**, Oxfordshire (GB);
Benjamin Mattin, Oxfordshire (GB)

(73) Assignee: **Crown Packaging Technology, Inc.**,
Alsip, IL (US)

(**) Term: **15 Years**

(21) Appl. No.: **29/733,869**

(22) Filed: **May 7, 2020**

(30) **Foreign Application Priority Data**

Nov. 8, 2019 (EM) 007207824

(51) **LOC (14) Cl.** **09-07**

(52) **U.S. Cl.**

USPC **D9/452; D9/454**

(57) **CLAIM**

The ornamental design for a metal container closure, as shown and described.

DESCRIPTION

FIG. 1 is a top perspective view of a metal container closure according to our design;

FIG. 2 is a bottom perspective view of the metal container closure of FIG. 1;

FIG. 3 is a top plan view of the metal container closure of FIG. 1;

FIG. 4 is a bottom plan view of the metal container of FIG. 1;

FIG. 5 is front-side elevation view of the metal container closure of FIG. 1;

FIG. 6 is a rear-side elevation view of the metal container closure of FIG. 1;

FIG. 7 is a left-side elevation view of the metal container closure of FIG. 1; and,

FIG. 8 is a right-side elevation view of the metal container closure of FIG. 1.

1 Claim, 8 Drawing Sheets
